UNITED STATES PATENT OFFICE.

FREDERICK E. SCHMIDT, OF BROOKLYN, NEW YORK.

BUTTON-HOLE SEWING-MACHINE.

SPECIFICATION forming part of Letters Patent No. 372,709, dated November 8, 1887.

Application filed October 30, 1886. Serial No. 217,555. (No model.)

To all whom it may concern:

Be it known that I, FREDERICK E. SCHMIDT, of the city of Brooklyn, county of Kings, and State of New York, have invented a new and 5 Improved Button-Hole Sewing - Machine, of which the following specification is a full, clear, and exact description.

This invention relates to a new construction of a button-hole sewing-machine, and has reference more particularly to that class of machines in which straight up-and-down motion only is imparted to the needle, while a lateral motion is imparted to the cloth-clamp. I propose to support the ratchet feed - wheel and 15 work-plate by a carrier-plate to which oscillating or reciprocating motion is transmitted by a rod directly from the operating-cam.

The invention consists in the various features of improvement more fully pointed out 20 in the claims.

In the accompanying drawings, Figure 1 is a bottom view of portion of the sewing-machine, exposing the operating mechanism. Fig. 2 is a face view of oscillating bar *g*; Fig. 3, a 25 back view of the same; Fig. 4, a perspective view of bent slide *s*; Fig. 5, a section on line *xx*, Fig. 1. Fig. 6 is a vertical longitudinal section, partly in side view, of the machine. Fig. 7 is a bottom view of the work-plate; Fig. 30 8, a top view thereof; Fig. 9, a bottom view of the ratchet feed-wheel, and Fig. 10 a top view thereof, showing it in position.

In button-hole sewing-machines, as is well known, the cloth-clamp is fed first toward the 35 needle, then describes a semicircle, and is then fed away from the needle. This motion is obtained from the revolution of the feed-wheel, having a slot in its upper face, which is entered into by a guide - pin projecting downward from the lower part of the cloth-clamp. This pin also passes through a slot in the work-plate, such slot being straight at the sides and curved in the middle, Fig. 7. By the co-operation of these parts, as is well known, the desired motion is imparted to the cloth-clamp. 40

Besides the revolving motion imparted to the feed - wheel, oscillating or reciprocating motion is imparted, in my machine, to the work-plate and with it to the cloth-clamp, 45 such motion being equal to the length of stitch. This motion I obtain from an oscillat-

ing or reciprocating carrier receiving motion from the operating-cam and supporting directly the ratchet-wheel, the work-plate, and the cloth-clamp, so that thus a double motion 55 is imparted to the cloth-clamp.

The letter *a* represents the bed-plate or table of a button-hole sewing-machine, this table being cut out beneath the head of the needle-bar to make room for a preferably circular 6c carrier, *b*, having an upwardly - projecting flange *c*. Upon the carrier *b* there rests the ratchet-wheel *d*, which is revolved, in manner hereinafter described, by means of pawls that engage such ratchet-wheel and enter through a 65 cut-away portion of flange *c*. To the flange *c* there is screwed the work-plate *e*, that covers ratchet-wheel *d*, and is provided with a slot having the form shown in Fig. 7. The upper face of ratchet-wheel *d* is grooved, Fig. 10, and into 70 this groove and through slot of plate *e* there enters a pin, *f*, attached to cloth-clamp *g*, as usual.

By the revolution of the wheel *d* the desired forward semicircular and backward motion is 75 imparted to the cloth-clamp.

To the carrier *b* oscillating or reciprocating motion is imparted, to impart corresponding motion to the ratchet-wheel, work-plate, and cloth-clamp. This oscillating or reciprocating 80 motion must be equal beneath the needle to the length of stitch desired, and is obtained as follows: The carrier *b* is pivoted by pin *h* to the table *a*, or to a suitable projection thereon. Opposite the pivot *h* the carrier *b* is provided 85 with a guide-pin, *i*, entering a slot, *k*, in table *a*. Upon the bottom of carrier *b* there is provided a curved groove, *l*, entered into by a pin, *m*, upon one end of bar *n*, the other end of which is provided with a pin, *o*. This pin 90 may be made to enter directly the groove of the operating-cam *p*, or it may be received by an intermediate oscillating mechanism, (shown in Figs. 1, 2, 3, 4, and 5,) which is designed to make the tack or closing stitches beneath the 95 button-hole. By the revolution of the cam *p* reciprocating motion is imparted to the bar *n* and oscillating motion around pivot *h* is imparted to the carrier *b*. By adjusting pin *m* within groove *l*, in greater or less proximity 100 to pivot *h*, the lateral motion of the carrier away from the needle may be regulated, and

thus the length of stitch may be adjusted. If desired, reciprocating instead of oscillating motion may be imparted to carrier *b*. In that case the pivot *h* is made to run in a slot similar to the pivot *i*.

If the tack of the button-hole is to be made, it is necessary to slightly shift the cloth-clamp, bringing it centrally under the needle, and it is also necessary to increase the motion of the cloth-clamp in both directions from the needle. The mechanism shown in Figs. 2 to 5 is designed to produce this result. It consists of a bar, *q*, oscillating on pin *r*, and having two inclined slots, *r' r''*, and a circular hole, *r³*. A pin, *r⁴*, on free end of bar *q*, enters the groove of operating-cam *p*. The lower slot, *r'*, is entered into by the pin *o* of bar *n*, such pin passing also through a bent front slide, *s*, Fig. 4, having a guide-pin, *t*, passing through upper slot, *r''*. A handle-shank, *u*, passes through circular hole *r³*, and has an eccentric-stud, *v*, entering a slot in slide *s*. By revolving the handle the slide *s* and a back slide, *s²*, are moved, the latter by pin *t*, toward or farther away from the cam *p*, and carry the pin *o* and rear end of bar *n* with them.

When the machine operates to sew the shanks and eye of the button-hole, the parts are in the position shown in Fig. 1, with the slide up. Motion is transmitted from cam *p* to pin *r⁴* of oscillating bar *q*, and thence by pin *o* to bar *n*; but when the tack is to be made the slide *s* is pushed down, and, owing to the inclined position of slots *r' r''*, it will throw the pin *o* farther away from the cam-groove. In this way the carrier *b* will be shifted, and at the same time its play in both directions will be increased.

It remains to be described how the ratchet-wheel *d* is revolved. From the cam *p* a lever, *a'*, receives oscillating motion, and imparts the motion to an oscillating bar or lever, *b'*. The lever *b'* is preferably connected by links *c' d'* to carrier *b*. To the link *d'* there are attached one or more pawls, *e'*, held against the teeth of ratchet-wheel *d* by spring or springs *f'*; but, if desired, the pawls *e'* may be attached directly to lever *b'*. By the revolution of cam *p* the levers *a' b'* are swung on their pivots, and thus the pawls *e'* will revolve ratchet-wheel *d*.

To decrease the play of levers *a' b'* when the tack of the button-hole is made, I pivot a bent rod, *g'*, to the table *a*. One arm of this rod is connected to slide *s*, while the other or free arm terminates a short distance above lever *b'*. When the machine sews the button-hole proper, the arm does not interfere; but when slide *s* is moved down, as previously described, to sew the tack, such free arm of rod *g'* will be brought over a knuckle, *h'*, on lever *b'*, and will thereby limit the motion of lever *b'*. Thus the feed of wheel *d* is diminished.

It is well known that while the eye of the button-hole is sewed the feed of ratchet-wheel *d* is to be quicker than when the shanks or straight sides are being sewed. This differ-

ence of motion is obtained (as described in my Patent No. 219,656 of September 16, 1879) by the alternate interposition and withdrawal of a small plug or elbow-lever, *i'*, between the contiguous ends of levers *a' b'*.

Motion is imparted to the plug as follows: Into the lower face of ratchet-wheel *d* there is cut a groove, *j'*, one half of which is larger than the other half, Fig. 9, as also described in the patent above referred to. This groove receives a pin, *k'*, projecting downward through a slot of carrier *b* and connected by links *l'* and spring-arms *m'* to the plug *i'*. As the pin *k'* enters alternately the larger or smaller sections of groove *j'*, the plug *i'* is introduced between or withdrawn from levers *a' b'*.

n' is a hand-ratchet to revolve wheel *d* when its position is to be changed. When the hand-ratchet is to be employed, the pawls *e'* must be first swung back to clear the teeth of ratchet-wheel *d*. In order to produce this result I employ a pivoted handle, *o'*, connected to a rod, *p'*, that in turn connects with a pivoted link, *q'*, having pin *s'*, Fig. 10, that is placed between ratchet-wheel *d* and pawl *e'*. By turning handle *o'* the pin *s'* will throw the pawl *e'* out of the ratchet-wheel. The handle *o'* is provided with an extension, *t'*, engaging a lug, *u'*, 95 on a friction-brake, *v'*, acting against the ratchet-wheel *d*. Thus the friction-brake will be thrown back at the same time with the pawl.

In place of using a ratchet-feed, *d*, a friction-feed may be employed. 100

I claim as my invention—

1. In a button-hole sewing-machine, the combination of a carrier-plate, cam, and connecting-rod, the said plate receiving lateral motion from the cam by means of the connecting-rod, with a feed-wheel having a cam-groove in its surface, and with a slotted work-plate and a cloth-clamp, which are superposed and supported on the carrier-plate so that the lateral motion of the carrier-plate is transmitted 105 to the feed-wheel, the work-plate, and the cloth-clamp, substantially as specified.

2. The combination, in a button-hole sewing-machine, of a flanged carrier-plate supporting the feed-wheel, the work-plate, and 110 the cloth-clamp, with an operating-cam and an arm connecting the carrier-plate with the cam, so that lateral motion is imparted to the carrier-plate, and with a feed mechanism engaging the feed-wheel so as to rotate the same, 115 substantially as specified.

3. The combination, in a button-hole sewing-machine, of a table and a carrier-plate pivoted to the table or a projection thereon with an operating-cam and a connecting-rod for 120 imparting motion to the carrier-plate, and with a feed-wheel, a work-plate, and a cloth-clamp supported by the carrier, and with a pawl engaging the feed-wheel, and with operating-levers for imparting alternately greater 125 and less motion to the pawl, substantially as specified.

4. The combination, in a button-hole sewing-machine, of a carrier-plate with a super-

posed feed-wheel, work-plate, and cloth-clamp, and with an oscillating bar, a slide, and an arm connecting the slide with the carrier, and with an operating-cam for imparting motion 5 to the oscillating bar, substantially as specified.

5. The combination, in a button-hole sewing-machine, of a carrier-plate and cam from which it receives lateral motion with a super-posed feed-wheel, work-plate, and cloth-clamp, 10 and with a spring-pawl engaging the feed-wheel, and with levers for imparting motion to said pawl from the operating-cam, and with a pin placed between the feed-wheel and the pawl and adapted to throw the pawl out of 15 engagement with the feed-wheel, substantially as specified.

6. The combination, in a button-hole sewing-machine, of a carrier-plate with a super-posed feed-wheel, work-plate, and cloth-clamp, and with an operating-cam for imparting lat- 20 eral motion to the carrier, and with a pawl engaging the feed-wheel, and with a pair of levers for imparting motion to the pawl, and with a bent rod and a slide to which one end of the bent rod is connected, while its other 25 end bears against one of said levers, substantially as specified.
